ROLL CALENDAR CASING FOR A WATCHBAND

Nils Jorgen Tvensberg, Kringsjaveien 25,
N-1415 Oppegaard, Norway

Filed Nov. 7, 1973, Ser. No. 413,707

Term of patent 14 years

Int. Cl. D19—03

U.S. Cl. D19—20

FIG. 1.

FIG. 2.

FIG. 3.

FIG. 1 is a perspective view of a roll calendar casing for a watchband embodying my new design;

FIG. 2 is a left side elevational view; and

FIG. 3 is a bottom plan view.

I claim:

The ornamental design for a roll calendar casing for a watchband, substantially as shown.
